FUSE CONSTRUCTION

Allan Ramsey, Evanston, Ill., assignor to
 Schweitzer & Conrad, Inc., Chicago, Ill., a corporation of Delaware

Application January 29, 1942, Serial No. 428,662

22 Claims. (Cl. 200—114)

My invention relates, generally, to the construction of electric circuit interrupters and it has particular relation to the construction of dropout fuses. This application is a continuation-in-part of my copending application, Serial No. 391,489, filed May 2, 1941, now Patent No. 2,290,382, issued July 21, 1942, as a division of my then copending application, Serial No. 166,945, filed October 2, 1937, now Patent No. 2,247,701, issued July 1, 1941.

An object of my invention is to provide for hingedly mounting at its upper end a fuse device that is retained in operative position at its lower end by means that is released on blowing of a fuse link within the device for disconnecting the same from the terminal at the lower end and providing an air gap therebetween.

Another object of my invention is to provide for mounting a dropout fuse device of this character within an insulating housing such as a porcelain or glass box.

A further object of my invention is to provide for slidably mounting both ends of a fuse tube on the cover of a box-type cutout.

Still another object of my invention is to provide for retaining the cover of a dropout fuse cutout in place after the fuse link therein has blown.

It is also an object of my invention to provide for urging the cover of a dropout fuse tube to an alternate position when the fuse link thereof is blown.

Other objects of my invention will, in part, be obvious and in part appear hereinafter.

For a more complete understanding of the nature and scope of my invention reference may be had to the following detailed description taken in connection with the accompanying drawings in which:

Figure 1 is a longitudinal sectional view of a preferred form of telescoping fuse device that can be employed in practicing my invention;

Figure 2 is a view, in side elevation, of one embodiment of my invention, this being a dropout fuse device of the open type;

Figure 3 is a detail top plan view of the upper circuit terminal shown in Figure 2;

Figure 4 is a detail bottom plan view of the lower circuit terminal shown in Figure 2;

Figure 5 is a longitudinal sectional view of an enclosed type of dropout fuse construction employing certain of the details of construction shown in Figures 1 and 2 of the drawings;

Figure 6 is a detail sectional view taken along the line 6—6 of Figure 5;

Figure 7 is a detail sectional view taken along the line 1—1 of Figure 5;

Figure 8 is a detail sectional view of the lower end of the fuse construction shown in Figure 5 and showing an alternate arrangement of the fuse link receiving terminal;

Figure 9 is a detail sectional view taken along the line 9—9 of Figure 5 and showing an alternate arrangement of the upper circuit terminal construction;

Figure 10 is a view, in side elevation, on a reduced scale, of the enclosed cutout construction shown in Figure 5 modified in accordance with the upper terminal construction shown in Figure 9 so as to permit the cover and associated fuse tube to swing away from the housing; and

Figures 11 and 12 are views in side elevation of an alternate form of lower terminal construction.

Referring first to Figure 2 of the drawings, it will be observed that the reference character 10 designates, generally, a mounting device for a fuse device, shown generally at 11. The mounting device 10 comprises a suitable support member, such as a channel base 12, and it has mounted at opposite ends thereof insulators 13 and 14 for supporting thereon upper and lower circuit terminals, shown generally at 15 and 16, respectively. Each of these circuit terminals 15 and 16 is provided with a circuit terminal plate 17 and 18, respectively, to which the circuit conductors can be connected, as will be readily understood.

In Figure 1 of the drawings the details of construction of the fuse device 11, except for the handling eyes shown in Figure 2, are more clearly illustrated. As shown in Figure 1 the fuse device 11 comprises an outer fuse tube or housing 21 with which is telescoped an inner fuse tube 22 having a liner 23. The housing or fuse tube 21 and the inner fuse tube 22 may be composed of suitable insulating material, such as a phenolic condensation product, while the liner 23 may be composed of fiber. Attention is directed to the well known fact that fiber, when subjected to the heat of an arc evolves an arc extinguishing medium that assists in extinguishing the arc. At its lower end the outer fuse tube or housing 21 is provided with a ferrule 24 that is threaded onto an externally threaded snap ring 25 mounted in a suitable peripheral groove, as shown, in the tube or housing 21. At its upper end the outer fuse tube or housing 21 is provided with an upper fuse terminal 26 that is threaded onto a suitable externally threaded snap ring 27 disposed in a suitable peripheral groove, as shown. The

upper fuse terminal 26 is apertured, as indicated at 28, and has threaded thereon a suitable cap 29. A rod-like terminal 30 extends from the upper fuse terminal 26 into the bore of the liner 23 inside of the inner fuse tube 22. A flanged head 31 is provided on the upper end of the rod-like terminal 30 and securely holds the rod-like terminal 30 in the aperture 28 when the cap 29 is screwed tightly into place.

The construction of the inner fuse tube 22 is similar to that of the outer fuse tube or housing 21. At its upper end the inner fuse tube 22 is provided with a ferrule 32 that is threaded on a suitable snap ring 33 located in a peripheral groove in the inner fuse tube 22. Snap ring 33 is provided with a shoulder 34 on its under side for engaging the inwardly projecting shoulder 35 of the ferrule 24 at the lower end of the outer fuse tube or housing 21 for limiting the outward movement of the inner fuse tube 22. The snap ring 33 is located in such position on the inner fuse tube 22 that, when the shoulder 34 thereof engages the inwardly projecting shoulder 35 of the ferrule 24, the lower end of the rod-like terminal 30 still projects into the bore of the liner 23. In this position the upper end of this bore is substantially closed and the building up of high gas pressure in the outer fuse tube or housing 21 is prevented.

With a view to biasing the inner fuse tube 22 outwardly with respect to the outer fuse tube or housing 21, a coiled compression spring 36 is interposed between the inner end of the fuse tube 22 and the under side of the upper fuse terminal 26 that closes the upper end of the outer fuse tube or housing 21. It will be observed that the spring 36 bears generally against the ferrule 32 rather than against the upper end of the inner fuse tube 22 itself. This construction prevents abrasion of the upper end of the inner fuse tube 22. It is desirable that the spring 36 be held in the upper closed end of the outer fuse tube or housing 21 when the inner fuse tube 22 moves downwardly. For this purpose the upper end turns of the spring 36 are threaded past the inwardly extending ears 37 of a washer 38 that is clamped between the under side of the upper fuse terminal 26 and the upper end of the outer fuse tube or housing 21.

The fuse tube or housing 21 and the inner fuse tube 22 are prevented from movement apart under the influence of the coil compression spring 36 by a fuse link, shown generally at 40, and positioned adjacent the lower open end of the inner fuse tube 22 which, it will be understood, forms an arc chamber lined with a material capable of evolving an arc extinguishing medium, i. e., the fiber liner 23. The fuse link 40 is of the replaceable type. It is provided at its upper end with a fuse link terminal 41 having a stud 42 integrally formed therewith for threading into the lower end of the rod-like terminal 30. Intermediate the ends of the fuse link terminal 41 there is provided a flange 43, the diameter of which is that of the stock from which the terminal is machined and underneath it there is a knurled portion 44 for receiving a sleeve 45, preferably formed of fiber, and preventing rotation thereof relative to the fuse link terminal 41. The lower end 46 of the link terminal 41 is deformed onto the upper ends of strain and fusible elements 47 and 48. The strain element 47 is preferably formed of a high strength wire, such as "Nichrome," while the fusible element 48 is preferably formed of silver. A sleeve 49 of suit-

able insulation may be positioned, as shown, around the strain element 47, if desired, to prevent the fusible element 48 from coming into contact engagement therewith. The fuse link 40 is provided with a lower fuse link terminal 50, the upper end 51 of which is deformed onto the lower ends of the strain and fusible elements 47 and 48. The fuse link terminal 50 is provided with a peripheral groove 52 in which is positioned a snap ring 53 for preventing the sleeve 45 from slipping out of position over the terminal 50. The lower end 54 of the fuse link terminal 50 is deformed onto a flexible conductor 55 that is formed by a large number of strands of fine wire and which is provided with a cone terminal 56 deformed thereon intermediate its ends. The lower fuse link terminal 50 will be free to move out of the lower end of the arcing chamber within the fuse tube 22 under the expulsion action of the blast of arc extinguishing medium on blowing of the strain and fusible elements 47 and 48. When this occurs the arc is drawn between the lower end of the rod-like terminal 30 and a lower fuse terminal 57 that is carried by and is movable with the inner fuse tube 22. It will be observed that the cone terminal 56 constitutes an anchor means for the lower end of the fuse link 40 and that it is positioned between ears 58 that are integrally formed with the rearwardly extending portion 59 of the lower fuse terminal 57. It will be observed that the lower fuse terminal 57 is threaded on a suitable split ring 60 that is located in a peripheral groove adjacent the lower end of the inner fuse tube 22. The mechanical interconnection provided by the flexible conductor 55 between the lower link terminal 50 and the lower fuse terminal 57 insures conjoint movement of these terminals and separation of the former from the rod-like stationary terminal 30.

As illustrated, the lower fuse terminal 57 is provided with an aperture 61 which leaves the bore of the liner 23 and the inner fuse tube 22 open and through which the flexible conductor 55 extends. By leaving the lower end of the inner fuse tube 22 open, the products of the arc formed on blowing of the fuse link 40 can readily escape and dangerous pressures are not built up within the fuse device 11, as might otherwise be the case if both ends of it were closed.

Referring again to Figure 2 of the drawings, it will be observed that the upper circuit terminal 15 includes a bifurcated support member in the form of a pair of relatively rigid wires 65, Figure 3, which are provided with upwardly opening hook-shaped portions 66 adjacent their outer ends for receiving a pair of arms or trunnions 67 which extend from opposite sides of the upper fuse terminal 26. Each of the arms or trunnions 67 has underneath it and spaced slightly therefrom a flange 68, extending from opposite sides of the upper fuse terminal 26 to prevent disengagement of the fuse device 11 from the upper circuit terminal 15 when it operates.

In order to mount the fuse device 11 in place, as shown in Figure 2, the upper fuse terminal 26 is also provided with an eye 69 for receiving the prong of a hook stick as will be readily understood. As shown more clearly in Figure 3 of the drawings the outer end portions 70 of the rigid wires 64 are flared outwardly and portions 71 are curved outwardly for guiding and gripping respectively the upper fuse terminal 26 as it is placed in operative position. This gripping action of the

portion 74 that is provided by the spreading apart slightly of the wires 65 when the upper fuse terminal 26 is placed therebetween provides the required contact pressure therewith.

With a view to latching the lower end of the fuse device 11 to the lower circuit terminal 16, the latter is provided with a pair of spaced apart spring fingers 75, Figure 4, the outer ends of which are provided with inwardly opening hook-shaped portions 76 for receiving therebetween ribs 77 formed integrally with the lower fuse terminal 57 that is carried by the lower end of the inner fuse tube 22 previously described. The outer ends of the spring fingers 75 are curved outwardly as indicated at 78 to facilitate entry of the lower fuse terminal 57 therebetween. An eye 79, integrally formed with the lower fuse terminal 57, is provided for receiving the prong of a hook stick so as to permit operation of the fuse device 21 to the latched position with respect to the lower circuit terminal 16.

In describing the operation of the fuse construction shown in Figures 1 through 4 of the drawings and described hereinbefore, it will be assumed that a fault has occurred on the circuit in which the device is connected and that sufficient current flows therethrough to blow the link 40 by fusing the fusible element 48 and the strain element 47. The coil compression spring 36 is no longer restrained and, therefore, it promptly moves the inner fuse tube 22 downwardly in the direction indicated by the arrow 86, Figure 2. The oppositely extending flanges 68 prevent the recoil from causing the fuse device 11 to move upwardly with respect to the upper circuit terminal 15. As soon as the ribs 77 clear the inwardly opening hook-shaped portions 76 of the contact fingers 75, the fuse device 11 is free to swing about the arms or trunnions 67 in the direction indicated by the arrow 81. This carries the lower fuse terminal 57 a substantial distance away from the lower circuit terminal 16 and provides a substantial air gap therebetween. This air gap is introduced into the circuit in addition to the air gap produced therein by the blowing of the link 40 which introduces an air gap between the lower end of the rod-like terminal 30 and the lower fuse terminal 57.

As will presently be apparent the details of construction of the dropout fuse shown in Figures 1, 2, 3 and 4 and described hereinbefore for an open type dropout fuse can be incorporated in what is known as an enclosed type of dropout fuse on the making of certain modifications.

Referring now particularly to Figures 5, 6 and 7 of the drawings, it will be observed that the reference character 85 indicates an insulating housing or box that may be formed of porcelain or glass or other suitable insulating material. The housing 85 is provided with an integrally formed top wall 86, side walls 87 and a rear wall 88. The bottom of the box is partially closed by a bottom wall 89, as shown. If desired, this bottom wall 89 may be omitted. On the outside of the rear wall there is provided a fitting 90 to facilitate mounting of the housing 85 on a suitable bracket as will be readily understood.

On the inside of the rear wall 88 there are provided upper and lower circuit terminals 91 and 92. Suitable apertures 93 and 94 are provided in the side walls 87 of the housing 85 for receiving line conductors for connection to the circuit terminals 91 and 92.

The upper circuit terminal 91 is provided with a combination support member and contact mem-

ber in the form of a U-shaped member having arms 98 which are urged toward each other by the arms 99 of a generally U-shaped spring member also carried by the upper circuit terminal 91, as shown. The outer ends of the arms 98 are hook-shaped and open upwardly as indicated at 100 for receiving the oppositely extending arms or trunnions 101 from an upper fuse terminal 102 which will be described in more detail hereinafter. The arms 98 are somewhat flexible and are urged into good contact engagement with the upper fuse terminal 102 by the arms 99 of the cooperating U-shaped spring.

The lower circuit terminal 92 is provided with a bifurcated contact member the arms 105 of which extend outwardly, as shown in Figure 7, and have inturned outer end portions 106 providing hook-shaped portions which, as illustrated, open inwardly. These outer end portions 106 are urged toward each other by the cooperating arms 107 of a U-shaped spring member that is nested therein. The outer end portions 106 are arranged to engage ribs 108 which are integrally formed with and extend laterally from a lower fuse terminal 109 the construction of which will be described in more detail hereinafter.

The front side of the housing 85 is arranged to be closed by a cover 110 that is formed of suitable insulating material such as a phenolic condensation product. It will be observed that the cover 110 is provided with a rearwardly extending portion 111 having a longitudinal aperture 112 extending therethrough. In effect this provides a housing or first fuse tube which corresponds to the housing or outer fuse tube 21 shown in Figure 1 of the drawings. It will be observed that the upper fuse terminal 102 is threaded into the rearwardly extending portion 111 at the upper end of the aperture 112 and that it is secured therein by means of a set screw 113. A rod-like terminal 114 projects downwardly from the terminal 102 and has at its upper end a flanged head 115 which rests against an inwardly extending flange 116 formed integrally with the terminal 102. A cap 116 is threaded on the upper fuse terminal 102, as shown, for holding the flanged head 115 and the rod-like terminal 114 in place. The rod-like terminal 114 extends into an inner fuse tube 117 which corresponds to the inner fuse tube 22 of the fuse device shown in Figure 1. The inner fuse tube 117 can be formed of fiber or it can be formed of other insulating material such as a phenolic condensation product having a liner 55 of fiber or other material as previously described.

It will now be observed that the lower fuse terminal 109 is mounted on the lower end of the inner fuse tube 117 and that it is secured in place thereon by means of set screws 118 and 119.

At its upper end the inner fuse tube 117 is provided with a ferrule 120 that is threaded thereon. A coil compression spring 121 disposed between the under side of the flange 116 and the upper side of a flange 122 serves to bias the inner fuse tube 117 downwardly. The downward movement of the inner fuse tube 117 is limited by the engagement of the lower end 123 of the ferrule 120 with a metallic ring 124 at the lower end of the longitudinal aperture 112 in the portion 111 of the cover 110.

The downward movement of the inner fuse tube 117 is restrained by a replaceable fuse link 128 which may be similar in construction to the 75 fuse link 40 described hereinbefore or it may be

constructed as illustrated in my Patent No. 2,144,707. Also, the spring fuse link construction shown in the copending application of Hugh A. Triplett, Serial No. 758,372, filed December 20, 1934, can be used if desired. The fuse link 128 includes a cone terminal 129 which is arranged to interfit with the bifurcated end of a foot portion 130 integrally formed with the lower fuse terminal 109.

When the fuse link 128 blows, the coil compression spring 121 is no longer restrained, and it promptly moves the inner fuse tube 117 downwardly until it and the lower fuse terminal 109 occupy the positions shown by the broken lines in Figure 5 of the drawings. The uppermost turn of the spring 121 is expanded so that it fits snugly within the upper terminal 102 and thereby is held in place after the fuse link 128 blows. It will be observed that the ribs 108 maintain contact engagement with the outer end portions 106 of the lower circuit terminal while the inner fuse tube 117 is moving through a substantial distance. Before separation takes place from the lower circuit terminal the arc incident to the blowing of the fuse link 128 will in most cases have been extinguished so that no arcing occurs between the ribs 108 and the lower circuit terminal.

As illustrated in Figure 5 of the drawings the cover 110 is provided with an integrally formed eye 131 to facilitate handling of the cover.

When the housing 85 is mounted in a substantially vertical position as illustrated in Figure 5 of the drawings, it is desirable that the cover 110 remain substantially as shown so as to fully close the front side of the housing 85. For this purpose the outer ends of the arms 98 forming the U-shaped combination support and contact member are provided with contact shoes 132 as shown in Figure 6 of the drawings. These contact shoes 132 are so shaped as to cooperate with the upper fuse terminal 102 and through the biasing force of the upper circuit terminal act to retain the upper fuse terminal 102 and hence the cover 110 in the position shown. However, on the application of sufficient force to the eye 131, it is possible to spread the contact shoes 132 against the biasing action of the upper circuit terminal provided by the arms 98 and 99 so as to permit the removal of the cover 110 and associated fuse tube 117 for replacing a blown fuse link 128.

As shown in Figure 7 of the drawings, the inward movement of the cover 110 is limited by bosses 136 integrally formed with the side walls 87 of the housing or box 85. This then insures that the ribs 108 will be properly placed with respect to the inturned ends 106 of the lower circuit terminal so as to provide good contact engagement therebetween.

In Figure 8 of the drawings there is shown an alternate form of lower fuse terminal construction. As shown, at the lower end of the inner fuse tube 117 there may be provided a lower fuse terminal 138 having integrally formed ribs, one of which is indicated at 139 to provide contact engagement with the lower circuit terminal while the fuse tube 117 is moving downwardly. A foot portion 140 is integrally formed with the lower fuse terminal 138 and its lower end is bifurcated for receiving a cone terminal 141 of a replaceable fuse link 142. A stud 143 is integrally formed with the lower fuse tube terminal 138 and on it is threaded a clamp nut 144 for clamping the end of the flexible lead 145 of the fuse link 142. 75

In the event that it is desired to mount the housing 85 in the position shown in Figure 10 of the drawings so as to more widely separate the lower fuse terminal from the lower circuit terminal, the contact shoes 132 are reversed from their positions shown in Figure 6 to the positions shown in Figure 9 of the drawings. When so located the resilient force of the upper circuit terminal acting through the arms 98 and 99 tends

10 to bias the terminal 102 and the door 110 outwardly so that, after the ribs 108 or 139 have moved out of latching engagement with the co-operating lower circuit terminal, the cover 110 and inner fuse tube 117 carried thereby can swing 15 to the position shown in Figure 10 of the drawings.

For mounting the housing 85 in the position shown in Figure 10 of the drawings an angle bracket 150 can be provided, as shown. The angle bracket 150 can be secured to a suitable clamp 20 151 which, as shown, is arranged to mount the assembly on a cross-arm 152.

In Figures 11 and 12 there is shown an alternate form of lower fuse terminal construction. Instead of integrally forming a foot portion 130 25 with the terminal 109, as shown in Figure 5 and described hereinbefore, a terminal 109' is provided the upper portion of which is the same as the terminal 109. However, a foot portion 154 is pivoted at 155 onto the lower end of the terminal 109' as shown. This foot portion 154 carries a slotted opening 156 for receiving the cone terminal 129 of the fuse link 128. If desired a threaded 30 stud and clamp nut can be used for securing the flexible lead to the foot portion 154, as shown in Figure 8. The flexible lead can also be passed over the foot portion 154 and secured to the terminal 109' by suitable means, such as a threaded stud and clamp nut as shown in Figure 8. This construction permits direct expulsion of the cone terminal 129 and associated parts of the fuse link 128 since they are maintained in alignment with the bore of the inner fuse tube 117 and do not extend over an edge thereof.

When the fuse link 128 blows, the resulting blast 45 aided by gravity causes the foot portion 154 to swing to the position shown in Figure 12 so as to provide a more free discharge from the fuse tube 17. The force causing the foot portion 154 to swing to the position shown in Figure 12 can be 50 augmented by a suitable spring.

Since certain further changes can be made in the foregoing constructions and different embodiments of the invention can be made without departing from the spirit or scope thereof, it is intended that all matters contained in the above description or shown in the accompanying drawings shall be considered as illustrative and not in a limiting sense.

I claim as my invention:

60 1. Circuit interrupting means comprising, in combination, a first circuit terminal having a first support means extending therefrom the outer end of which is bifurcated and hook-shaped opening upwardly, a second circuit terminal having a second support means extending therefrom the outer end of which is bifurcated and hook-shaped opening inwardly, a first fuse tube, a second fuse tube 65 telescoped with said first fuse tube, a first fuse terminal closing one end of said first fuse tube and having a pair of oppositely extending arms for mounting in said upwardly opening hook-shaped end of said first support means, a second terminal at one end of said second fuse tube but leaving the same open, said second terminal having a pair 70 of oppositely extending ribs for mounting in said

inwardly opening hook-shaped end of said second support means, said fuse tubes being biased apart, and a conductor including a fusible section interconnecting said first and second fuse terminals and restraining said fuse tubes from movement apart as long as said fusible section remains intact, said second terminal on blowing of said fusible section moving out of engagement with said second support means and said first terminal rotating in said first support means with said fuse tubes, whereby an air gap is formed between said second terminal and said second support means.

2. Circuit interrupting means comprising, in combination, a first circuit terminal having a first support means extending therefrom the outer end of which is bifurcated and hook-shaped opening upwardly, a second circuit terminal having a second support means extending therefrom the outer end of which is bifurcated and hook-shaped opening inwardly, a first fuse tube, a second fuse tube telescoped with said first fuse tube, a first fuse terminal closing one end of said first fuse tube and having a pair of oppositely extending arms for mounting in said upwardly opening hook-shaped end of said first support means, means on said first fuse terminal interfitting with said first support means and arranged and adapted to prevent separation thereof except when the former is moved to a predetermined position relative to the latter, a second terminal at one end of said second fuse tube but leaving the same open, said second terminal having a pair of oppositely extending ribs for mounting in said inwardly opening hook-shaped end of said second support means, said fuse tubes being biased apart, and a conductor including a fusible section interconnecting said first and second fuse terminals and restraining said fuse tubes from movement apart as long as said fusible section remains intact, said second terminal on blowing of said fusible section moving out of engagement with said second support means and said first terminal rotating in said first support means with said fuse tubes, whereby an air gap is formed between said second terminal and said second support means.

3. Circuit interrupting means comprising, in combination, a first circuit terminal, support means associated with said terminal, a second circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal, means projecting from opposite sides of said fuse tube adjacent said lower end thereof for engaging said bifurcated hook-shaped outer end of said retaining means, said fuse tube being biased downwardly with respect to said housing, and a conductor including a fusible section interconnecting said first and second fuse terminals and restraining downward movement of said fuse tube as long as said fusible section remains intact, said second fuse terminal on blowing of said fusible section moving out of engagement with said second circuit terminal whereby an air gap is provided therebetween.

4. Circuit interrupting means comprising, in combination, a first circuit terminal, support means associated with said terminal, a second

circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal, means projecting from opposite sides of said fuse tube adjacent said lower end thereof for engaging said bifurcated hook-shaped outer end of said retaining means, said fuse tube being biased downwardly with respect to said housing, a conductor including a fusible section interconnecting said first and second fuse terminals and restraining downward movement of said fuse tube as long as said fusible section remains intact, said second fuse terminal on blowing of said fusible section moving out of engagement with said second circuit terminal whereby an air gap is provided therebetween, and contact means associated with said second fuse terminal for maintaining contact engagement with said second circuit terminal while the former is moving relative to the latter through a substantial distance.

5. Circuit interrupting means comprising, in combination, a first circuit terminal, support means associated with said terminal, a second circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal, means projecting from opposite sides of said fuse tube adjacent said lower end thereof for engaging said bifurcated hook-shaped outer end of said retaining means, said fuse tube being biased downwardly with respect to said housing, a conductor including a fusible section interconnecting said first and second fuse terminals and restraining downward movement of said fuse tube as long as said fusible section remains intact, said second fuse terminal on blowing of said fusible section moving out of engagement with said second circuit terminal whereby an air gap is provided therebetween, and clamp means on said second fuse terminal for connecting one end of said conductor thereto.

6. Circuit interrupting means comprising, in combination, a first circuit terminal, support means associated with said terminal, a second circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal including a portion fast on said fuse tube and a foot portion hingedly mounted thereon and disposed in line with the bore of said

fuse tube and adapted to swing away therefrom, means projecting from opposite sides of said fuse tube adjacent said lower end thereof for engaging said bifurcated hook-shaped outer end of said retaining means, said fuse tube being biased downwardly with respect to said housing, and a conductor including a fusible section interconnecting said first and second fuse terminals and restraining downward movement of said fuse tube as long as said fusible section remains intact, one end of said conductor engaging said hinged foot portion and holding the same in alignment with said bore as long as said fusible section remains intact, said second fuse terminal on blowing of said fusible section moving out of engagement with said second circuit terminal whereby an air gap is provided therebetween.

7. Circuit interrupting means comprising, in combination, a first circuit terminal having a first support means extending therefrom the outer end of which is bifurcated and hook-shaped opening upwardly, a second circuit terminal having a second support means extending therefrom the outer end of which is bifurcated and hook-shaped opening inwardly, a housing, a first fuse terminal on said housing having a pair of oppositely extending arms for mounting in said upwardly opening hook-shaped end of said first support means, a fuse tube telescoped with said housing, a second fuse terminal at the lower end of said fuse tube, said second terminal having a pair of oppositely extending ribs adapted to be received in said bifurcated inwardly opening hook-shaped end of said second support means and providing electrical connection to said second circuit terminal, said fuse tube being biased downwardly with respect to said housing, and a conductor including a fusible section interconnecting said first and second fuse terminals and restraining downward movement of said fuse tube as long as said fusible section remains intact, said second fuse terminal on blowing of said fusible section moving out of engagement with said second support means whereby an air gap is provided therebetween.

8. Circuit interrupting means comprising, in combination, a first circuit terminal, support means associated with said terminal, a second circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal, means projecting from opposite sides of said fuse tube adjacent said lower end thereof for engaging said bifurcated hook-shaped outer end of said retaining means, a coil compression spring biasing said fuse tube downwardly with respect to said housing, and a conductor including a fusible section interconnecting said first and second fuse terminals and restraining downward movement of said fuse tube as long as said fusible section remains intact, said second fuse terminal on blowing of said fusible section moving out of engagement with said second circuit terminal whereby an air gap is provided therebetween.

9. Circuit interrupting means comprising, in combination, a first circuit terminal, support

means associated with said terminal, a second circuit terminal below said first circuit terminal, retaining means associated with said second circuit terminal, the outer end of said retaining means being bifurcated and hook-shaped opening inwardly, a housing, a fuse tube telescoped with said housing, a first fuse terminal carried by said housing at its upper end for engaging said first circuit terminal, means carried by said housing for pivotally supporting the same on said support means, a second fuse terminal at the lower end of said fuse tube for engaging said second circuit terminal, means projecting from opposite sides of said fuse tube adjacent said lower end thereof for engaging said bifurcated hook-shaped outer end of said retaining means, a coil compression spring within said housing biasing said fuse tube downwardly with respect to said housing, stop means limiting the downward movement of said fuse tube relative to said housing, and a conductor including a fusible section interconnecting said first and second fuse terminals and restraining downward movement of said fuse tube as long as said fusible section remains intact, said second fuse terminal on blowing of said fusible section moving out of engagement with said second circuit terminal whereby an air gap is provided therebetween.

10. Circuit interrupting means comprising in combination, a first circuit terminal having a first support means extending therefrom the outer end of which is bifurcated and hook-shaped opening upwardly, a second circuit terminal having a second support means extending therefrom the outer end of which is bifurcated and hook-shaped opening inwardly, a housing, a first fuse terminal on said housing having a pair of oppositely extending arms for mounting in said upwardly opening hook-shaped end of said first support means, a fuse tube telescoped with said housing, a second fuse terminal at the lower end of said fuse tube, said second terminal having a pair of oppositely extending ribs adapted to be received in said bifurcated inwardly opening hook-shaped end of said second support means and providing electrical connection to said second circuit terminal, a coil compression spring biasing said fuse tube downwardly with respect to said housing, and a conductor including a fusible section interconnecting said first and second fuse terminals and restraining downward movement of said fuse tube as long as said fusible section remains intact, said second fuse terminal on blowing of said fusible section moving out of engagement with said second support means whereby an air gap is provided therebetween.

11. Circuit interrupting means comprising, in combination, a first circuit terminal having a first support means extending therefrom the outer end of which is bifurcated and hook-shaped opening upwardly, a second circuit terminal having a second support means extending therefrom the outer end of which is bifurcated and hook-shaped opening inwardly, a housing, a first fuse terminal on said housing having a pair of oppositely extending arms for mounting in said upwardly opening hook-shaped end of said first support means, a fuse tube telescoped with said housing, a second fuse terminal at the lower end of said fuse tube, said second terminal having a pair of oppositely extending ribs adapted to be received in said bifurcated inwardly opening hook-shaped end of said second support means and providing electrical connection to said

second circuit terminal, a coil compression spring within said housing biasing said fuse tube downwardly with respect to said housing, stop means limiting the downward movement of said fuse tube relative to said housing, and a conductor including a fusible section interconnecting said first and second fuse terminals and restraining downward movement of said fuse tube as long as said fusible section remains intact, said second fuse terminal on blowing of said fusible section moving out of engagement with said second support means whereby an air gap is provided therebetween.

12. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, and an insulating cover for closing said front of said housing and having means integrally formed therewith for slidably supporting both ends of said fuse tube and guiding the same, one of said fuse terminals for said fuse device being fixed to said cover and the other being fixed to and movable with said fuse tube away from said one fuse terminal, said fuse tube being restrained from movement by said fuse link and being biased for movement relative to said cover when said fuse link blows.

13. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insulating cover for closing said front of said housing and having means integrally formed therewith for slidably supporting both ends of said fuse tube and guiding the same, one of said fuse terminals for said fuse device being fixed to said cover and the other being fixed to and movable with said fuse tube away from said one fuse terminal, said fuse tube being restrained from movement by said fuse link and being biased for movement relative to said cover when said fuse link blows, and means for limiting the movement of said fuse tube relative to said cover after blowing of said fuse link.

14. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, and an insulating cover for closing said front of said housing and having a sleeve portion integrally formed therewith and extending over a substantial portion of the inner side thereof for slidably supporting both ends of said fuse tube and guiding the same, one of said fuse terminals for said fuse device being fixed to said cover and the other being fixed to and movable with said fuse tube away from said one fuse terminal, said fuse tube being restrained from movement by said fuse

link and being biased for movement relative to said cover when said fuse link blows.

15. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insulating cover for closing said front of said housing and having means integrally formed therewith for slidably supporting both ends of said fuse tube and guiding the same, one of said fuse terminals for said fuse device being fixed to said cover and the other being fixed to and movable with said fuse tube away from said one fuse terminal, and spring means biasing said fuse tube downwardly with respect to said cover, the downward movement of said fuse tube being restrained by said fuse link.

16. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insulating cover for closing said front of said housing and having means integrally formed therewith for slidably supporting both ends of said fuse tube and guiding the same, one of said fuse terminals for said fuse device being fixed to said cover and the other being fixed to and movable with said fuse tube away from said one fuse terminal, and spring means biasing said fuse tube downwardly with respect to said cover, the downward movement of said fuse tube being restrained by said fuse link, and means for stopping the downward movement of said fuse tube relative to said cover when the former has reached a predetermined position relative to the latter.

17. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insulating cover for closing said front of said housing and having means integrally formed therewith for slidably supporting both ends of said fuse tube and guiding the same, one of said fuse terminals for said fuse device being fixed to said cover and the other being fixed to and movable with said fuse tube away from said one fuse terminal, and coil compression spring means reacting between said cover and said fuse tube for biasing the latter downwardly with respect to the former, the downward movement of said fuse tube being restrained by said fuse link.

18. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insu-

lating cover for closing said front of said housing and having a sleeve portion integrally formed therewith and extending over a substantial portion of the inner side thereof for slidably supporting both ends of said fuse tube and guiding the same, one of said fuse terminals for said fuse device being fixed to said cover and the other being fixed to and movable with said fuse tube away from said one fuse terminal, and spring means biasing said fuse tube downwardly with respect to said cover, the downward movement of said fuse tube being restrained by said fuse link.

19. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, an insulating cover for closing said front of said housing and having a sleeve portion integrally formed therewith and extending over a substantial portion of the inner side thereof for slidably supporting both ends of said fuse tube and guiding the same, one of said fuse terminals for said fuse device being fixed to said cover and the other being fixed to and movable with said fuse tube away from said one fuse terminal, and coil compression spring means reacting between said cover and said fuse tube for biasing the latter downwardly with respect to the former, the downward movement of said fuse tube being restrained by said fuse link.

20. Circuit interrupting means comprising, in combination, an insulating housing having rear, top and side walls and open at the front, circuit terminals carried by said housing one above the other, and a fuse device for interconnecting said circuit terminals having fuse terminals at its ends for engaging said circuit terminals and including a fuse tube adapted to receive a fuse link for interconnecting said fuse terminals, and an insulating cover for closing said front of said

5 housing and having means integrally formed therewith for slidably supporting said fuse tube and guiding the same, the upper of said fuse terminals being supported on and carried by said cover, the lower of said fuse terminals being supported on and carried by said fuse tube.

21. Circuit interrupting means comprising, in combination, upper and lower circuit terminals, insulating means supporting said circuit terminals in spaced relation one directly above the other, a fuse device for interconnecting said circuit terminals having fuse terminals at its ends for engaging said circuit terminals and including a fuse tube adapted to receive a fuse link for interconnecting said fuse terminals, said fuse tube being biased to slide downwardly and restrained by said fuse link, means pivotally mounting said fuse device adjacent said upper circuit terminal, and means associated with said upper circuit terminal and cooperating with the fuse terminal engaged therewith for retaining said fuse device in position thereon after blowing of said fuse link and downward movement of said fuse tube.

25 22. Circuit interrupting means comprising, in combination, upper and lower circuit terminals, insulating means supporting said circuit terminals in offset relation in the same vertical plane with respect to each other, a fuse device for interconnecting said circuit terminals having fuse terminals at its ends for engaging said circuit terminals and including a fuse tube adapted to receive a fuse link for interconnecting said fuse terminals, said fuse tube being biased to slide downwardly and restrained by said fuse link, means pivotally mounting said fuse device adjacent said upper circuit terminal and permitting the same to swing under the influence of gravity away from said lower circuit terminal on blowing of said fuse link, and means associated with said upper circuit terminal and cooperating with the fuse terminal engaged therewith for urging said fuse device to swing outwardly on blowing of said fuse link.
